METHOD AND APPARATUS FOR CONTROL
OF SUPERHEAT BY GAS MASS FLOWCharles E. Lucke, New York, N. Y., assignor to
The Babcock & Wilcox Company, Newark,
N. J., a corporation of New Jersey

Application August 30, 1934, Serial No. 742,048

9 Claims. (Cl. 122—479)

This invention relates to fluid heat exchange apparatus in which heat is transferred from hot gases sweeping across spaced tubes, to a fluid within the tubes. The invention is herein exemplified as an interdeck superheater.

An object of the invention is to maintain a constant superheat throughout a varying range of boiler loads by creating variations in the mass flow of the heating gases over a part of the tube surface at a given total flow rate.

A specific object of the invention is to provide a superheater in which the gas mass flow over part of the superheater surface is varied for the purpose of obtaining a more constant superheat, independently of such variations as are due to changes of boiler load while all gases at all times sweep the superheater heating surface.

Other objects of the invention will appear as the accompanying description proceeds.

20 The invention will be described with reference to the accompanying drawings in which Fig. 1 is a view in the nature of a vertical section showing a water tube steam boiler having an interdeck superheater to which the invention is applied. 25 The superheater is here shown adjusted for light boiler loads.

Figs. 2, 3 and 5 are diagrammatic views indicating different adjustments of the illustrative apparatus, all three of them for boiler load conditions which are intermediate those of light load and full load.

Fig. 4 is a diagrammatic view indicating the adjustment of the apparatus when the boiler is under full load.

35 Fig. 6 is a diagrammatic view of the apparatus indicated in Fig. 1 of the drawings, illustrating a control mechanism for operating the dampers to cause the mass flow of the gases across the superheater to be varied in response to changes in boiler load.

In Fig. 1 of the drawings there is shown an interdeck superheater 10, preferably consisting of return bend tubes connected to superheater headers 12 and 14 which are located externally of the boiler gas pass. The superheater is disposed between an upper bank 16 of steam generating tubes, and a lower bank 18 of similar tubes. These steam generating tubes extend across the path of furnace gases leaving the furnace 20. The steam generating tubes 18 connect headers 22 and 24 from which nipples 26 and 28 extend upwardly to similar headers 30 and 32 connected by the steam generating tubes 16. The steam and water drum 34 is connected to the headers 30 and

32 in a well known manner by horizontal circulators 36 and downtake nipples 38.

It has been an undesirable characteristic of convection superheaters that they do not maintain a constant superheat when the boiler load changes. They naturally operate so as to produce a gradually increasing superheat when the boiler load is increased. Such variation of the superheat with the boiler load is limited or prevented by this invention through the application of devices which may vary the gas mass flow past the superheater at any load and which are adjusted to counteract the natural tendency of the superheater to give a varying and increasing superheat as the boiler load increases.

15 Investigations of heat transfer have proven that the unit rate in B. t. u./hr./sq. ft./degree between the hot gas and the tubes increases with an increase of gas mass flow, lb. of gas/hr./sq. ft. of mean stream section, and in a regular manner. 20 When the boiler load is light the gas temperature and the gas mass flow are both low in comparison with a heavy load, and the superheat which is also relatively low can be raised by an increase of gas mass flow at light load. This is 25 accomplished by varying the gas flow path past the superheater tubes so that at light load there is a lesser flow area or gas stream cross section and consequently a higher gas mass flow. This increases the unit heat transfer rate and increases 30 the heat transferred per hr. per sq. ft. so that the superheat is higher than it otherwise would be, and the variations of superheat unit boiler load are also lessened or entirely eliminated.

35 Considering the apparatus as it is shown in Fig. 1 of the drawings, the furnace gases proceeding across the steam generating tubes 18, pass across the superheater tubes in three passes in series. Such gas flow action is caused in the present instance by the upright fixed baffles 40 and 42 and the movable baffles or mass flow controllers now to be described.

Fig. 1 shows two movable baffles 44 and 46 which are preferably pivoted at 48 and 50 upon supports 52 and 54 secured to the steam generating tubes 18. These two movable baffles are located at the bottom of a gas pass or space between the fixed baffle 42 and the downtake connections or nipples 28. When they are adjusted as shown in dotted lines in Fig. 1 the furnace 45 gases may flow from the furnace directly upwardly from a position in front of the headers 24 and they have this position at full boiler load. At times of low boiler load these baffles are adjusted as shown in full lines in Fig. 1 and they, 50 55

in substance, operate as a solid baffle extending along the upper tubes of the lower bank of steam generating tubes to prevent flow of gases from the furnace directly upward.

5 There are three more pairs of movable baffles, one pair above the gas pass between the fixed baffle 40 and the wall 26, and a pair at the top and bottom of the gas pass between the two fixed baffles 40 and 42. Such baffles are indicated by 10 numerals 55-60 inclusive. These movable baffles may have the positions indicated by the full lines in Fig. 1, or those indicated by the dotted lines, or any intermediate position. The full line positions are for light boiler load. The gases then 15 make three passes in series over the superheater, while the dotted line positions allow the gases to make a single pass in three parallel sections for full boiler load. The full load position provides about three times the gas flow area and one third 20 the gas mass flow of the light load position, and intermediate positions permit of graduation of area and mass flow between these limits.

Each of the movable baffles above described 25 may be provided with any suitable mechanism for holding it in open or closed position or in any intermediate position so as to effect any desired control of the mass flow of gases across the superheater. All of these movable baffles are shown moved to their open position for full load in Fig. 30 4 of the drawings.

In Figs. 2, 3 and 5 the movable baffles are shown 35 in intermediate positions for a boiler load between a full load or a light load.

It is an outstanding characteristic of the present invention that all of the furnace gases must 40 at all times proceed across and sweep some part of the superheating surface, regardless of the control which is exercised upon the mass flow of the gases by the apparatus here disclosed. There is no by-passing of gases around the superheater surfaces and consequently there is no condition, 45 beyond the superheater surfaces, wherein there are two separate gas streams of such widely variant temperatures as exist in the case wherein some of the furnace gases are by-passed around the superheater.

Regulating apparatus to cause the mass flow 50 of the gases across the superheater to be so varied in response to changes in boiler load that excessive changes in superheat are prevented, is indicated diagrammatically in Fig. 6 of the drawings. Referring to this figure, and considering the boiler load as changing from light to full load, the first load increase causes the diaphragm operator 55 62 to move the dampers 57 and 58 to their open position. The next increase causes the dampers 55, 56, 59 and 60 to be simultaneously moved to their open positions by action of the operator 64. A further increase involves the action of the operator 66 in opening the dampers 44 and 46.

The diaphragm operators may be operated in sequence through changes in the fluid pressure in the line 68, caused by a proper shaping of the lands 10 and 72 of a pilot valve 74 which may be 65 of the nature of the valve shown in the patent to Johnson No. 2,054,464, dated Sept. 15, 1936, and the axial movement of the valve stems of the spring loaded operators 64 and 66 may be mechanically amplified, or hydraulically amplified by the use of such a mechanism as that indicated 70 in the patent to Jones 1,972,853, September 11, 1934, or the patent to Albright 1,922,834, August 15, 1933.

The pilot valve rod 76 may be operated in response to changes in boiler load through such

apparatus as that shown in Fig. 6. Here, this rod is connected to a lever 78 linked to a Bourdon tube 80 actuated by temperature changes in the fluid in the capillary 82 which communicates with a member 84 sensitive to temperature changes in the superheater outlet header 12.

The lever 78 may also be subject to control by a flow meter 86 which uses saturated steam pressure through the line 88 and superheater outlet pressure through the line 90 as a measure of the 10 flow of steam, or boiler load.

With further reference to the pilot valve 74 and its operation, the space between the two lands 10 and 72 is constantly under air pressure. Furthermore, air is constantly flowing past the 15 lands on all sides, in order to have an effect in the nature of a lubricating effect, upon the lands. This circumferential air stream is, however, so thin that the air pressure may be maintained in the space between the lands. The land 72 is 20 so shaped that the flow of air from the space between the lands 10 and 72 into the line 68 increases as the land 72 moves downward from a position wherein its position of maximum diameter is just above the axis of the inlet of the 25 tube 68, the maximum pressure being created in the line 68 when the top of the land 72 has moved well below the axis of the inlet of the tube 68.

The Bourdon tube 80 is responsive to temperature changes in the superheated steam in the 30 header 12, and when that temperature increases the free end of the Bourdon tube will be elevated, so as to have a tendency to elevate the left hand end of the lever 78 through the link connecting the lever to the Bourdon tube. If this action 35 causes the pilot valve rod 76 to be raised, the land 72 will be raised and the pressure in the line 68 will be decreased. However the influence of the Bourdon tube 80 may be counteracted by the influence of the flow meter 86 which uses the difference 40 between saturated steam pressure in the line 88 and the pressure of the superheated steam in the line 90 as a measure of steam flow. When steam flow increases, the action of the flow meter 86 tends to elevate the right hand end of the lever 45 78 and pivot it around its connection with the link depending from the Bourdon tube 80. If this fulcrum point remains fixed the pivot valve rod 76 will be lowered and the fluid pressure in the line 68 will be increased.

What is claimed is:

1. In combination, a steam boiler including a bank of steam generating tubes, a furnace from which hot gases pass across the steam generating tubes, a superheater contacted at all times by all of the gases which have passed across the generating tubes, a first set of gas flow regulators contacting with the furnace gases before they reach the superheater, gas baffling means beyond said set of regulators and defining gas flow passages across said superheater, and another set of gas flow regulators positioned beyond the superheater with reference to gas flow and co-operable with the first set of flow regulators and with said baffling means to cause the gases to 60 pass across the superheater in a single pass or in a plurality of passes, said sets of regulators cooperating to cause the mass flow of the gases across the superheater to be varied.

2. In combination, a furnace, steam generating 70 tubes across which gases pass from the furnace, a superheater having tubes positioned beyond the steam generating tubes relative to gas flow and arranged so that all of the furnace gases must at all times contact with superheater sur- 75

face, a baffle transversely related to the superheater tubes, and gas flow controllers so associated with the superheater and the baffle as to regulate the mass flow of gas over the super-

5 heater surface in inverse ratio to changes in boiler load or superheater steam exit temperature and thereby prevent excessive variations of the latter, there being a plurality of the controllers forwardly of the superheater and beyond the superheater with reference to gas flow whereby the gases may be caused to pass across the same superheater surface in a plurality of passes or in a single pass depending upon the load imposed upon the boiler.

10 15 3. In the production of superheated steam for power purposes, causing the mass flow of heating gases across a superheater to be increased or decreased inversely as the boiler load changes, said action including the causing of furnace gases 20 to flow in series and in successive gas passes over successive parts of the superheater.

4. In a single pass water tube steam boiler, banks of steam generating tubes, an interdeck convection superheater, and means to cause the furnace gases to pass across the superheater in three passes under full boiler load and in one pass under light boiler load.

5. In a single pass steam boiler, a furnace, vertically spaced banks of steam generating tubes 30 over which hot gases pass from the furnace, a convection superheater having a bank of tubes positioned between said banks of tubes so that all of the furnace gases at all times pass over superheater surface, spaced upright baffles extending 35 across the bank of superheater tubes but not across the steam generator tubes, one of the upright baffles terminating short of the top of the superheater bank while a second terminates short of the bottom of the superheater bank, uptake 40 and downtake headers at opposite ends of the generating tubes, two pairs of independently adjustable baffles capable of forming a substantially continuous baffle compelling all of the furnace gases to pass between the uptake headers and 45 the first of said fixed baffles, and two pairs of independently adjustable baffles capable of forming a substantially continuous baffle extending from the uptake headers above the superheater bank to a position above the top of the second fixed baffle.

50 6. In the generation of superheated steam, passing furnace gases over steam generating surface and superheating surface in series, causing a uniformly high mass flow over the entire

superheater surface at low boiler load and a uniformly low mass flow over the entire superheater surface at high boiler load, and varying the mass flow of heating gases over the superheater inversely to boiler load changes.

7. In a steam boiler, a furnace, a bank of steam generating tubes extending across the gas flow from the furnace, a superheater including spaced tubes positioned beyond the generating tubes with reference to gas flow and contacted by the furnace gases leaving the generating tubes, baffles extending across the superheater and defining a plurality of superheater sections, and dampers forwardly and rearwardly of the superheater with reference to gas flow, said dampers co-acting with the baffles to cause the gases to flow optionally in series or in parallel over the superheater sections and operating to vary the fraction of gases flowing in series or in parallel while maintaining gas contact with all sections of the superheater.

8. In a steam boiler, a furnace, a bank of steam generating tubes extending across the gas flow from the furnace, a superheater including spaced tubes positioned beyond the generating tubes with reference to gas flow and contacted by the furnace gases leaving the generating tubes, baffles extending across the superheater and defining a plurality of gas flow passages with superheater tubes in each passage, means for causing the gases to flow wholly or partly in series or in parallel through said gas flow passages and over the superheater tubes, and means for maintaining gas flow through all of the passages.

9. A method of superheating steam and controlling its final temperature comprising the steps of subjecting enclosed and spaced currents of steam to the heating effect of furnace gases passing between the currents in sufficient weight ratio of gases to steam to produce a predetermined superheat, maintaining such utilization of the gases that they do not bypass zones in which they are effective upon the steam, controlling the flow of gases in such manner that the ratio of the effective area available for heat exchange between the gases and the steam currents to that of the whole superheater surface is increased when the steam temperature is too high and decreased when the steam temperature is too low, said ratio changes taking place independently of the total hourly weight of gases or steam flowing.

CHARLES E. LUCKE.
